UNITED STATES PATENT OFFICE.

CLARENCE A. TRIPP, OF MOJAVE, CALIFORNIA.

CAN OPENER.

Application filed February 3, 1921. Serial No. 442,104.

To all whom it may concern:

Be it known that I, CLARENCE A. TRIPP, a citizen of the United States, residing at Mojave, in the county of Kern and State of California, have invented new and useful Improvements in Can Openers, of which the following is a specification.

It is the object of this invention to provide a can opener of extremely simple construction and so arranged as to be particularly applicable for use in connection with a can having a top provided with a peripheral bead, the can opener being so constructed as to provide supports at the respective sides of the cutting blade for engagement against the main portion of the top and against the peripheral bead of the same during the rocking motion of the opener for cutting the top.

20 The invention will be readily understood from the following description of the accompanying drawings, in which

Figure 1 is a perspective view of a can engaged by the opener for cutting the top of 25 the same.

Fig. 2 is a similar view looking in the opposite direction and showing the opposite side of the can opener.

Fig. 3 is a side elevation of the can opener 30 showing the side thereof which engages the main portion of the can top.

Fig. 4 is a similar view showing the opposite side of the can opener.

Fig. 5 is an end view of the can opener.

35 Fig. 6 is a longitudinal section on the line 6-6 of Fig. 3.

The improved can opener is particularly adapted for use in connection with a can provided with a peripheral bead 1 extending 40 an appreciable distance above the main portion 2 of the can top.

The can opener comprises a handle portion, preferably formed of a looped strip of metal as shown at 3 with the portions of the looped strip brought together at the lower end of the handle as shown at 4, and then arranged in longitudinally parallel and transversely spaced relation as shown at 5 so as to form a support for the cutting 50 blade.

One of the ends 5 of the looped metal strip terminates in a transversely disposed plate 6 extending along the side of the strip end and projecting beyond the edges of said side 55 in upwardly curved ends 7. When the de-

vice is in use the plate 6 rests against the main portion 2 of the can top and the handle of the can opener is adapted to be rocked back and forth so as to bring the ends 7 of the plate against the can top.

60 A strip 8 is arranged between the ends 5 of the handle forming strip and extends longitudinally along the inner surface of the strip end 5 carrying plate 6. At its lower end the strip 8 terminates in a plate 9, extending the width of strip end 5 and terminating in upwardly curved end projections 10. The plate 9 is longitudinally spaced above plate 6 a distance equal to the width of bead 1 provided upon a can, so that 70 plate 9 will rest against said bead while plate 6 rests against the main portion of the can.

A blade 11 is mounted between strip ends 5 and projects longitudinally beyond the same, the shank of this blade being, preferably, received against the inner surface of the second strip end 5 with a spacing block 12 between said shank and the strip. The parts as thus described may be held together by rivets 13 received through the spacing block, the shank of the blade, the strip 8 and the ends 5 of the handle strip.

75 By reference to Fig. 5, it will be seen that blade 11 is in alignment with plate 9, and in practice the longitudinally projecting cutting portion of the blade is preferably extended through a slot 14 provided in plate 9. The cutting portion of the blade, preferably, tapers downwardly to a point 15 and 80 is provided at its opposite sides with cutting edges 16, so that the can opener may be moved in either direction around the periphery of a can. In use it will be understood that the blade pierces the top of the 90 can until plates 6 and 9 rest against the can top, and when in this position the blade is, preferably, held against withdrawal from the can by providing notches 17 in the cutting edges of the blade just below plate 6 and consequently at the portion of the blade in alignment with the material forming the 95 can top.

In order to prevent lateral displacement of the can opener, as thus described, the 100 strip end 5 opposite the one carrying plate 6 is, preferably, provided with a laterally offset longitudinally extending end 18 adapted to extend down over the side of a can when the opener is in use. By this ar- 110

2
arrangement it will be seen that after the cutting blade has pierced the can top, the extension 18 will laterally position the can opener, and plate 6 and 9 will limit the depth to which the can opener extends into the can so as to bring the cutting blade into operative position, it being understood that the can opener is operated by swinging the same back and forth upon plates 6 and 9 and the 10 upwardly curved ends of the same.

Various changes may be made without departing from the spirit of the invention as claimed.

What is claimed is:

15. 1. A can opener comprising a handle formed of a looped strip, a blade received between said loop ends and projecting beyond the same, one of said loop ends forming an abutment plate received against the 20 side of a can and the other loop end forming an abutment plate received against the can top, and a strip extending longitudinally beyond said second loop end and forming an abutment plate received against the bead of 25 said can top.

2. A can opener comprising a handle, a blade projecting from one end thereof, a transversely disposed abutment plate having upturned ends arranged between the handle 30 and the blade, and a second abutment plate arranged below and to one side of the first mentioned abutment plate, and additional

means for preventing lateral displacement of said blade.

3. A can opener comprising a handle, a 35 blade projecting from one end thereof, an abutment plate arranged between the handle and the blade, a second abutment plate arranged below and to one side of the first mentioned abutment plate, and both of said 40 abutment plates having up-turned ends.

4. A can opener comprising a handle, a 45 blade projecting from one end thereof, an abutment plate arranged between the handle and the blade, a second abutment plate arranged below and to one side of the first 50 mentioned abutment plate, and a guiding member extending downwardly from the lower end of the handle and spaced apart from said blade.

5. A can opener comprising a handle, a 55 blade projecting from one end thereof, an abutment plate arranged between the handle and the blade, a second abutment plate arranged below and to one side of the first mentioned abutment plate, both of said abutment plates having up-turned ends, and a guiding member extending downwardly from the lower end of the handle and spaced apart 60 from said blade.

In testimony whereof I have signed my name to this specification.

CLARENCE A. TRIPP.
